A. JUHÁSZ

BARBER CHAIR REGISTER

Filed Jan. 23, 1922

Patented Mar. 13, 1923.

1,448,448

UNITED STATES PATENT OFFICE.

ANDREW JUHÁSZ, OF CHICAGO, ILLINOIS.

BARBER-CHAIR REGISTER.

Application filed January 23, 1922. Serial No. 531,157.

To all whom it may concern:

Be it known that I, ANDREW JUHÁSZ, citizen of Hungary, residing at Chicago, in the county of Cook and State of Illinois, have invented certain new and useful Improvements in Barber-Chair Registers, of which the following is a specification.

This invention relates generally to barbers' chairs having more particular reference to a counting device whereby the number of customers occupying the chair during a day, or any other selected period of time, may be registered.

The invention has for an object to provide a simple form of mechanism as above set forth which is actuated by the weight of the customer when the latter sits on the chair.

For further comprehension of the invention, and of the objects and advantages thereof, reference will be had to the following description and accompanying drawings, and to the appended claim in which the various novel features of the invention are more particularly set forth.

Fig. 1 of the drawings is a side view, with certain exterior parts broken away, of a barber's chair having the invention applied thereto.

Fig. 2 is a rear view, with the lower part of the pedestal omitted.

Fig. 3 is a detail transverse section on the line 3—3 of Fig. 1.

Fig. 4 is a detail transverse section on the line 4—4 of Fig. 1.

Fig. 5 is a detail transverse section on the line 5—5 of Fig. 1.

Referring now to the drawings the reference numeral 10 indicates the usual supporting pedestal of a barber's chair. The seat of the chair comprises a floor-like lower plate 11, rigidly fixed on the pedestal 10, and a vertically movable top plate 12 which is spaced some distance above the member 11 and may be suitably upholstered, the covering 13 of the upholstery extending downward at the front as at 13' across the space between the two plates 11 and 12 and being attached to the lower plate 11.

The back of the chair is hollow like the seat, and comprises a rigid rear wall 16, and a suitably upholstered front wall 17, the usual headrest being indicated at 18. The pedal 10 is provided with the usual tilting mechanism indicated at 19.

Fixed to the underside of the top plate 12 of the seat are a number of posts such as

20 which project slidably into socket elements 21 fixed on the lower plate 11. Surrounding these posts 20 are coiled expansion springs 22 which bear between the sockets 21 and the top plate 12 and resiliently support the latter. The amount of vertical movement of the seat element 13 is determined by studs such as 23 fixed in the posts 20 and engaging in vertical slots such as 24 in the sockets 21.

Fixed to the top plate 12 is a downwardly projecting rack bar 25 the teeth whereof mesh with a gear 26 fixed to one section 27 of a horizontal shaft extending longitudinally within the hollow seat and supported by bearings indicated at 28. The other section 27', of the shaft has fixed thereon a bevel gear 29 meshing with a bevel gear 30 fixed on the lower end of a shaft 31 extending up the hollow back. On the upper end of shaft 31 is fixed a bevel pinion 32 meshing with a bevel gear 33 rigid with a dial-disk 34 having any selected series of numbers marked on its rearwardly facing surface as indicated at 35 in Fig. 5.

To form a one-way connection between the shaft sections 27 and 27' the former has feathered on its rear end a ratchet faced clutch element 37 pressed into engagement with a like clutch element 38, on the forward end of section 27', by a spring 39. Reverse movement of shaft section 27' is prevented by a spring pressed pawl 40 engaging a ratchet wheel 41 fixed shaft section 27'.

To permit of resetting of the dial-disks 34 it is mounted so that it may be moved bodily rearward to disengage the gear 33 from the pinion 32, a spring being provided 95 which is gradually wound as the dial turns and which returns the dial to its starting position. With the above purpose in view the disk 34 is swiveled on forward end of a stud 42 whose rear end engages freely in a socket 43 fixed in a box 44 projected rearwardly from the back member 16.

A spiral spring 45 is coiled around the stud 42 and has one end connected to the latter and the other end connected to the disk 34. Fixed to the rear end of the stud 42 is a handle 46 which projects through an angular slot 47 in the socket 43, this slot presenting a transverse arm and a rearwardly extending longitudinal arm, the gear 33 being in mesh with the pinion 32 when handle is engaged in the transverse arm of

slot 47, the rotary pressure of spring 45 on the stud 42 tending to hold the handle 46 engaged in the transverse arm of slot 47. The rear face of box 44 is covered by a glass 5 paned door 50 hinged thereto and provided with a suitable lock.

In the operation of my improved device, when a customer sits in the chair, the top place 13 of the seat is depressed, causing rack 25 to rotate gear 26 imparting movement to shafts 27, 27' and 31 and rotating the dial disk 34 one number and imparting a winding movement to spring 45. It is to be understood that the clutch members 37 and 38, and 15 the ratchet wheel 41, will each have a number of teeth having the same relation to the total numbers on dial 34 that the bevel pinion 32 has to the gear 33. When the customer rises from the chair gear 26 and shaft 27 are rotated in an opposite direction but 20 the other parts remain stationary by reason of the engagement of pawl 40 with ratchet wheel 41.

When the dial is to be reset the handle 46 is moved first in a circular path to register 25 with the longitudinal arm of slot 47, and

then rearwardly to free gear 33 from pinion 32, spring 45 rotating the dial back to zero as soon as the gear 33 disengages from the pinion 32, the dial being provided with 30 a lug 60 which engages the dial pointer 61 and holds the dial at zero position.

Having thus described my invention what I claim as new and desire to protect by Letters Patent of the United States is as follows:

In a barber's chair, a movable element, a dial-disk, means providing an operative connection between said movable element and dial-disk including a gear fixed to said disk, 40 and means for moving said disk and gear axially to displace said operative connection, said means comprising a stud on which said disk is swiveled, a socket in which said stud is supported, and a handle on said stud projecting through an angular slot in said socket and a spring connected to said disk adapted to return the same to zero position.

In testimony whereof I have affixed my signature.

ANDREW JUHASZ.
